DESIGN FOR A BOTTLE CARRIER

Donald K. Washburn, Huntington Park, Calif.

Application July 25, 1938, Serial No. 78,694

Term of patent 14 years

To all whom it may concern:

Be it known that I, Donald K. Washburn, a citizen of the United States, residing at Huntington Park, in the county of Los Angeles and States of California, have invented a new, original, and ornamental, Design for a Bottle Carrier, of which the following is a specification, reference being had to the accompanying drawing, forming part thereof.

Figure 1 is a plan view of the bottle carrier showing my design,

Figure 2 is a front elevation thereof, and,

Figure 3 is an end elevation thereof.

My design is characterized by a bottle carrier

of the configuration shown comprising a skeletonized body formed of upper and lower rectangular continuous side wall strips having rounded corners, said strips being held in spaced relation by closely spaced medially arranged flat end strips having connected thereto the lower ends of an upwardly extending bail like handle, and the bottom of the carrier being formed of a pair of spaced flat strips disposed in the particular relationship shown.

I claim:

The ornamental design for a bottle carrier, as shown and described.

DONALD K. WASHBURN.
